UNITED STATES PATENT OFFICE

2,369,279

BALANCED RUDDER

Edwin D. Carnaghan and Frank Carnaghan,
Los Angeles, Calif.

Application December 29, 1943, Serial No. 516,073

2 Claims. (Cl. 114—166)

The present invention relates to new and useful improvements in rudders, particularly for air and water craft, and has for its primary object to provide, in a manner as hereinafter set forth, a device of this character comprising a unique arrangement of blades whereby maximum efficiency will be had.

Another very important object of the invention is to provide a multiple blade rudder of the aforementioned character which, when installed on a ship, will function properly and be equally effective whether the vessel is going forward or in reverse.

Still another very important object of the invention is to provide a control surface which is adapted to function as an elevator on airplanes and submarines.

Other objects of the invention are to provide a multi-bladed rudder which will be comparatively simple in construction, strong, durable, highly efficient and reliable in operation, compact and which may be manufactured at low cost.

All of the foregoing, and still further objects and advantages of the invention will become apparent from a study of the following specification, taken in connection with the accompanying drawings wherein like characters of reference designate corresponding parts throughout the several views, and wherein:

Figure 1 is a view in side elevation of a rudder constructed in accordance with the present invention, showing said rudder installed on the stern of a vessel, a portion of said vessel being broken away in section.

Figure 2 is a top plan view, showing the rudder installed on the tail assembly of an airplane.

Figure 3 is a view in front elevation of the rudder.

Figure 4 is a vertical sectional view, taken substantially on the line 4—4 of Figure 3.

Figure 5 is a view in horizontal section, taken substantially on the line 5—5 of Figure 3.

Referring now to the drawings in detail, it will be seen that reference character 1 designates a vertical post, which, in Figure 1 of the drawings, is rotatably mounted on the stern 2 of a vessel 3. Suitable bearings 4 are provided for the post 1.

Fixed on the lower portion of the post 1 is a plurality of spaced, parallel, vertical blades 5 of suitable metal. The blades 5 are connected, at their upper and lower ends, by transverse bars 6 having aligned openings therein through which the post 1 passes. In the embodiment shown, the members 5 and 6 are formed from a single

length of metal in the form of what may be considered a rectangular coil the upper and lower portions of the turns of which are in abutting engagement and soldered, welded or otherwise secured together.

It is thought that the operation of the invention as thus far described will be readily apparent from a consideration of the foregoing. Of course, as the vessel 3 moves forwardly or in reverse, the water flows freely through the spaces 7 between the vertical blades 5. When the post 1 is turned in the usual manner, all of the blades 5 present surfaces to the water at an angle to the direction of travel for maximum effectiveness. As the post 4 extends centrally through the device, the rudder is balanced and will function properly and with equal effectiveness whether the vessel 3 is moving forwardly or in reverse.

In Figure 2 of the drawings, the rudder is shown mounted for operation on the tail assembly 8 of an airplane 9 between the elevators 10 of said assembly. As hereinbefore mentioned, the device may also be installed to function as an elevator on an airplane or a submarine. When thus used, the device is rotated vertically.

It is believed that the many advantages of a rudder constructed in accordance with the present invention will be readily understood, and although preferred embodiments are as illustrated and described, it is to be understood that changes in the details of construction and in the combination and arrangement of parts may be resorted to which fall within the scope of the invention as claimed.

What is claimed is:

1. A control surface comprising a post, and a substantially rectangular metallic coil fixed on the post, certain opposite portions of the coil being in abutting engagement with each other and secured together, the portions of said coil between said certain portions extending in spaced parallelism to each other and constituting a gang of blades.

2. A control surface comprising a post, and a substantially rectangular metallic coil fixed on said post, certain opposite portions of the coil being in abutting engagement with each other and secured together, the portions of said coil between said certain portions extending in spaced parallelism to each other and constituting a gang of blades, said gang of blades extending in vertical relation in substantial parallelism with respect to said post.

EDWIN D. CARNAGHAN.
FRANK CARNAGHAN.
